TURBINE EXHAUST

David H. Silvern, Olean, N. Y.

Application March 17, 1953, Serial No. 342,780

5 Claims. (Cl. 253—39)

This invention relates to an improvement for discharging an elastic fluid from axial flow machines; more particularly, this invention pertains to means for collecting and discharging the elastic fluid leaving the final blade wheel of an axial flow turbine.

Turbines, by and large, convert the pressure head available in an elastic fluid or gas such as steam, air or combustion gases, into useful energy. The elastic fluid discharges from the blades of the last turbine stage at comparatively high velocity and low pressure. This high velocity decreases through the gas outlet passageway and generally the ultimate exhaust pressure is less than the pressure of the gas leaving the blades, indicating that energy losses occur in the outlet passageway to dissipate velocity and pressure alike. Numerous proposals have been advanced in the art for minimizing these energy losses in the outlet passageway but to date none has been found to reduce these losses to a material extent.

An object of this invention is to provide a structure which avoids the loss of pressure head in the outlet passageway of an axial flow turbine.

A further object is to provide a turbine outlet structure which converts the high velocity of the gas exhausting from the blades of the last turbine wheel into pressure while efficiently directing the exhaust gas away from the turbine blades.

Other objects and advantages of the invention will be apparent from the description which follows.

In the accompanying drawings forming a part of the specification and showing for exemplification a preferred form of this invention:

Figure 1 is a schematically illustrated cross-sectional view of the turbine outlet structure; and

Figure 2 is a section through line 2—2 of Figure 1.

An axial flow turbine 10, partially represented, discharges the gas from blades 12 of its last stage in a generally axial direction, i. e., parallel to rotor shaft 14. The gas flows without any change of direction into diffuser 16 which, according to well known principles, translates gas velocity into a static pressure head. Diffuser 16, which is an annular passageway that is gradually flared outwardly relative to the rotor shaft 14, starts with a substantially straight section having a length generally more than twice the height of the blades 12 in the last turbine stage. Ordinarily, the length of the straight section of diffuser 16 is at least one foot. The cross-sectional area of diffuser 16 gradually increases along its length to the order of two or three times its area adjacent blades 12. A critical feature of proper diffuser design is the requirement of symmetrical gas flow therethrough without substantial change in the direction of gas flow.

At a point where diffusion is substantially completed, diffuser 16 ends in a radial turn 18 which has the function of redirecting the gas from its substantially axial flow to radial flow. By and large, the gas leaves radial turn 18 radially, i. e., at right angles to the rotor shaft 14. In radial turn 18 too, it is essential that the gas flow

2

symmetrically. Any asymmetrical gas flow in turn 18 appears to react back on diffuser 16 and the turbine itself. After symmetrically completing this change in direction of flow, the gas passes from radial turn 18 through a set of guide vanes 20 which again change the direction of flow.

As shown in Figure 2, the set of vanes 20 is designed to send the gas around collector ring 22 toward exhaust conduit 24. Therefore, vane 20a directly in line with exhaust 24 is straight, that is, is aligned with a plane passed through it and the turbine axis. The others are individually curved relative to a plane passed through the innermost point thereof, that is, the point on the vanes closest to the radial axis of the turbine, and the turbine axis, each according to the angle through which the gas must be deflected to flow toward exhaust 24. The end vanes 20b which are farthest from exhaust 24 tend to divide the gas at the bottom of ring 22 so that half flows around each side of collector ring 22. As can be seen in Figure 2, each vane is so angled as to direct the gas laminar which flows over it towards the exhaust 24, with the angles of the individual vanes, as illustrated, being such that the sum total of all the laminae from all of the vanes on each side of the plane through vane 20a and the turbine axis, substantially filling the collector ring. The individual vanes 20 are preferably joined into a unitary structure by two flat rings 30. Thus, all the vanes 20 may be prepositioned in proper relationship to each other and the assembly inserted at the entrance to the collector ring 22. Alternatively, each vane 20 may be individually positioned and fastened to the side walls of collector ring 22.

The presence of vanes 20 is of critical importance. Transforming the symmetrical axial and radial flows into the generally rotational asymmetrical flow in collector ring 22 is best effected by deflecting forces applied by vanes 20. In the absence of vanes 20, the asymmetrical flow occurring in collector ring 22 appears to cause great turbulence and to react upstream on diffuser 16 by building up the back pressure and reducing turbine output.

It has been found important to have each change of direction of gas flow substantially completed, before commencing a new change of direction. Thus, the gas has substantially completed turning from a substantially axial flow direction in diffuser 16 to a direction radially outward from rotor shaft 14, before it is redirected around collector ring 22 toward exhaust conduit 24. The separation of the angular displacements effected by radial turn 18 and guide vanes 20 is essential to the successful operation of this invention. It has been found that positioning vanes 20 further upstream, i. e., inside radial turn 18, builds up a back pressure thereby decreasing turbine efficiency.

Collector ring 22 gradually increases in cross-section from a minimum adjacent vanes 20b to a maximum adjacent the entrance to exhaust conduit 24. The actual relative dimensions of collector ring 22 are proportioned in conformity with the volumes of gas entering all along its inner edge from between the vanes 20. The exhaust conduit 24 will ordinarily exhaust to a condenser in the case of a steam turbine, and to a regenerator in the case of a gas turbine.

A combustion gas turbine built according to the principles of this invention with the final stage of turbine blades 4 inches high, a diffuser (straight section) 18 inches long, a radial turn ending at 90° to the rotor axle, and 37 guide vanes equidistantly spaced around the entrance to the collector ring delivered 4300 horsepower. Without the guide vanes, the same turbine delivered only 4,000 horsepower.

While this invention has been described in connection with an axial flow turbine, it is not limited thereto. Axial

flow compressors likewise deliver gas from the blades of the last stage in an annular stream flowing substantially axially. Embodying the structure of this invention in the outlet passageway of an axial flow compressor to remove the compressed gas will increase compressor efficiency.

In view of the various modifications of the invention which will occur to those skilled in the art upon consideration of the foregoing disclosure without departing from the spirit or scope thereof, only such limitations should be imposed as are indicated by the appended claims.

What is claimed is:

1. An exhaust for use in an axial flow turbine comprising a diffuser beginning at the last stage of the turbine and terminating in a radial turn for diverting the axial flow of the turbine gases into a radial flow; a radially extending collector ring, having a single exhaust conduit opening, surrounding and opening into the radial turn for collecting the gases exhausting therefrom and thereafter exhausting the collected gases through its exhaust conduit; a plurality of vanes separating the radial turn and the collector ring with the individual vanes so curved away from radial planes through the turbine axis as to separate the gases into two parts with both parts being simultaneously directed around opposite sides of the collector ring towards the exhaust conduit.

2. An exhaust for use in an axial flow turbine comprising a diffuser beginning at the last stage of the turbine and terminating in a radial turn for diverting the axial flow of the turbine gases into a radial flow; a radially extending collector ring, having a single exhaust conduit, surrounding and opening into the radial turn for collecting the gases exhausting from the radial turn and then exhausting the collected gases through the exhaust conduit; a plurality of vanes separating said radial turn and collector ring with the vanes being divided into two oppositely oriented groups and the vanes of each group extending from the radial turn towards the collector ring and each vane being angled towards the collector exhaust conduit relative to radial planes through the turbine axis to split the gases radially flowing from the radial turn into two simultaneously flowing circumferential streams with each stream flowing only through one half of the collector ring towards the exhaust conduit and the streams flowing in opposite directions.

3. A construction as defined in claim 2, and each vane being oriented at a greater angle towards the collector exhaust conduit than the preceding vane starting with the vanes most distant from the exhaust conduit to laminate the opposite flowing streams, with each gas laminar of the streams being directed towards the collector ex-

haust conduit and with the stream laminations filling the collector ring.

4. A gas turbine exhaust for an axial flow turbine for changing the axial flow of gas first into a radial flow and then into a circumferential flow divided into two major, oppositely and simultaneously flowing sections directed towards an exhaust opening, comprising: an axial flow diffuser in the form of an outer cylindrical wall spaced from and surrounding an inner cylindrical wall beginning at the last stage of the turbine and terminating in a radial turn for directing the axial flow of the gases between said walls through the diffuser then to exhaust the gases radially of the diffuser, a radially extending collector ring surrounding and opening into the radial turn and having a collector exhaust; guide vane means positioned between the radial turn and the collector ring and arranged for directing the radial flow of gases into the collector ring in a circumferential flow of two sections with the sections simultaneously flowing, each through one half of the collector ring, towards the collector exhaust and with one section flowing in a clockwise direction and the other in a counter-clockwise direction, said guide vane means comprising a plurality of vanes arranged to surround the radial turn with each vane extending in a direction from the radial turn towards the collector ring with the vanes being divided into two groups, the vanes of one group being curved towards the collector exhaust in one direction relative to radial planes through the turbine axis and the vanes in the other group being curved towards the collector exhaust in the opposite direction.

5. A construction as defined in claim 4, and each vane being curved at a greater angle towards the collector exhaust than the preceding vane starting with the vanes most distant from the collector exhaust to laminate the oppositely flowing gas sections with each gas laminar being directed towards the collector exhaust and with the gas laminations arranged to completely fill the collector ring.
